UNITED STATES PATENT OFFICE.

CARL L. YOUNG AND ALBERT B. ROBERTSON, OF AMARILLO, TEXAS.

BOAT-PROPELLION MEANS.

Application filed November 29, 1927. Serial No. 236,437.

This invention relates to new and useful improvements in boat propulsion and embodies novel improvements therein, the main object being to provide means of this character in which a maximum amount of speed may be secured by spending a comparatively small amount of power.

In the practical embodiments of the invention, the boat will be provided with a longitudinal packing or tube in the hull thereof, adapted to receive water at its front end and deliver the water from its rear end, a pulling propeller being mounted in the front end of the tube and a pushing propeller being arranged within the rear end of the tube, for causing the rapid flow of the water therethrough.

This arrangement creates a vacuum in front of the ship and eliminates the vacuum at the rear end of the ship, thereby reducing resistance, and causing the boat to run more level over high swells or waves.

In the drawings:—

Figure 1 is a side elevation of a boat constructed in accordance with one form of the invention.

Fig. 2 is an enlarged longitudinal section through the forward end of the tube arranged upon the hull of the boat, and within which is mounted an operating propeller.

Fig. 3 is a front end of the ship constructed in accordance with the present invention.

Fig. 4 is a view similar to Fig. 1, disclosing a slightly modified form of construction, and

Fig. 5 is a fragmentary front elevation of this modification.

First having reference to Figs. 2 and 3, 5 designates a generally conventional boat, the hull of which is formed throughout its entire length with a tube or passage 6, preferably of circular shape in cross section.

Mounted within each end of this tube or passage 6 is a spider 7 formed centrally with a longitudinally extending sleeve 8. Mounted within the sleeve of each spider is a short propeller shaft 9, the outer end of which is equipped with a generally conventional boat propeller 10.

The inner end of each propeller shaft 9 is universally attached as at 11 to inwardly and upwardly extending power shafts 12. As in-

dicated by the dotted lines in Fig. 1, these power shafts 12—12 are operatively associated with a power plant 13 arranged within the boat 5.

Obviously, the movement of the boat thru the water will cause the suction of the water at the forward end of the boat, whereupon the water will enter the tube 6 and move fastly through the medium of the propellers 10, at the front and rear end of said tube. This will cause the smooth riding of the boat upon the water, and will eliminate the vacuum at the rear end of the boat, which retards the speed of boats now generally in use.

The modifications disclosed in Figs. 4 and 5 consist of a longitudinally extending tube or passage 6' formed directly within the hull of the boat 5', the opposite ends of this tube or passage being slightly raised as clearly indicated. The forward end of this tube or passage 6' has arranged therein, a suitable grille 14 for preventing the entrance of foreign matter into said tube or passage.

In this instance, the boat 5' is equipped with a pair of power plants 13'—13', from which extend horizontal power shafts 15—15, the rear ends of which pass through the raised ends of the tube or passage 6' and that are equipped at the ends of this tube or passage with suitable propellers 16—16. Substantially the same results are secured in this instance, as in the construction indicated in Figs. 1, 2 and 3.

Having this described our invention, what we claim as new is:—

In a boat propulsion means, a longitudinal water tube arranged at the bottom side of the hull of the boat and being open at its opposite ends, the spider arranged within each end of the tube, a sleeve extending through each spider and projecting forwardly and rearwardly thereof, a stub shaft mounted for rotation within said sleeve, a propeller on the outer end of each shaft, and power driven shafts universally connected to the respective inner ends of the respective stub shafts.

In testimony whereof we affix our signatures.

CARL L. YOUNG.
ALBERT B. ROBERTSON.
